(57) CLAIM

The ornamental design for an electronic vaping device, as shown and described.

DESCRIPTION

FIG. 1 is a perspective view of a first embodiment of a new design for an electronic vaping device.

FIG. 2 is a front view of the electronic vaping device of FIG. 1.

FIG. 3 is a back view of the electronic vaping device of FIG. 1.

FIG. 4 is a left side view of the electronic vaping device of FIG. 1.

FIG. 5 is a right side view of the electronic vaping device of FIG. 1.

FIG. 6 is a top view of the electronic vaping device of FIG. 1.

FIG. 7 is a bottom view of the electronic vaping device of FIG. 1.

FIG. 8 is a perspective view of another embodiment of a new design for an electronic vaping device.

FIG. 9 is a front view of the electronic vaping device of FIG. 8.

FIG. 10 is a back view of the electronic vaping device of FIG. 8.

FIG. 11 is a left side view of the electronic vaping device of FIG. 8.

FIG. 12 is a right side view of the electronic vaping device of FIG. 8.

FIG. 13 is a top view of the electronic vaping device of FIG. 8.

FIG. 14 is a bottom view of the electronic vaping device of FIG. 8.

FIG. 15 is a perspective view of another embodiment of a new design for an electronic vaping device.

FIG. 16 is a front view of the electronic vaping device of FIG. 15.

FIG. 17 is a back view of the electronic vaping device of FIG. 15.
 FIG. 18 is a left side view of the electronic vaping device of FIG. 15.
 FIG. 19 is a right side view of the electronic vaping device of FIG. 15.
 FIG. 20 is a top view of the electronic vaping device of FIG. 15; and,
 FIG. 21 is a bottom view of the electronic vaping device of FIG. 15.
 Broken lines in the drawings depict features that form no part of the claimed design.
